(57) **CLAIM**

The ornamental design for a disposable toilet seat cover, as shown and described.

DESCRIPTION

FIG. 1 is a perspective front view of a disposable toilet seat cover shown in use with a toilet, showing our new design; FIG. 2 is a perspective front view of the disposable toilet seat cover;

FIG. 3 is a perspective rear view of thereof;

FIG. 4 is a top view of the disposable toilet seat cover shown in a flattened state with a bottom view being a mirror image;

FIG. 5 is a front view thereof;

FIG. 6 is a rear view thereof; and,

FIG. 7 is a left side view thereof with a right side view being a mirror image.

The broken line showing of a toilet in FIG. 1 is for the purpose of illustrating environmental structure and forms no part of the claimed design.
